United States Patent Office

Des. 208,824
Patented Oct. 3, 1967

208,824

JUG

Richard L. Platte, Ann Arbor, Mich., assignor to Hoover
Ball and Bearing Company, Saline, Mich., a corporation
of Michigan

Filed Nov. 28, 1966, Ser. No. 4,836

Term of patent 14 years

(Cl. D58—5)

FIG. 1

FIG. 2

FIG. 3

FIGURE 1 is a side elevational view of a jug, showing my new design;

FIGURE 2 is a rear elevational view; and

FIGURE 3 is a top plan view.

The dominant features of my new design reside in the portions shown in full lines.

I claim:

The ornamental design for a jug, substantially as shown and described.
